UNITED STATES PATENT OFFICE.

JOHN L. REAM, OF AXTELL, KANSAS.

ADJUSTABLE COLLAR.

1,347,712.

Specification of Letters Patent.

Patented July 27, 1920.

Application filed August 8, 1919. Serial No. 316,151.

To all whom it may concern:

Be it known that I, JOHN L. REAM, a citizen of the United States, residing at Axtell, in the county of Marshall and State of Kansas, have invented a new and useful Adjustable Collar, of which the following is a specification.

This invention relates to improvements in harness, and more particularly to the collar construction thereof.

The primary object of the invention is to provide an adjustable collar, capable of being expanded and contracted to fit animals of various sizes.

It is of course known that horse collars, are manufactured in standard sizes, and it is obvious that these collars do not always fit, to the comfort of the animal wearing the same, with the result that the animal's neck becomes bruised and sore, rendering the animal temporarily incapacitated for further work.

A further object of the invention is to provide a collar capable of a fine adjustment, thereby insuring an exact fit to the animal's neck wearing the same, thus eliminating unnecessary rubbing between the collar and neck of the user.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed without departing from the spirit of the invention.

Referring now to the drawing:—

Figure 1 illustrates a bottom plan view of a portion of a collar having my invention attached thereto.

Fig. 2 is a top plan view of the buckle used in connection with my invention.

Fig. 3 is an end elevational view of the buckle, and;

Fig. 4 is a sectional view taken on line 4—4 of Fig. 3.

Having reference to the drawing in detail, the collar as shown includes the opposed sections 1' and 2', the upper ends thereof being pivotally connected together by the usual and well known hook and loop connection, not shown, the lower ends thereof being split to provide the end members 3 and 4.

The end 3, is formed into a tongue member 3' provided with a plurality of openings 4' disposed in spaced relation throughout the length of the tongue 3, the opposed end 60 4 of the collar section 2, has secured thereto the permanent buckle member 5, which includes a base 6 provided with openings 7 through which pass rivets or similar securing means 8.

Adjacent the forward end of the buckle 5, is a right angular loop section 9 of a length equal to the length of the base 6, said loop member having an offset section 10 formed integral and adapted to provide a 70 clearance for the usual connecting strap of the hames, which are supported by the collar.

Formed integral with the opposite end of the buckle 5, and spaced from each other, are 75 the upwardly extending lugs 11, said lugs extending upwardly and terminating on a plane with the top of loop member 9.

As shown, the buckle member 5 is secured to one of the collar sections, the opposing 80 end of the adjacent collar section, or tongue 3' being inserted through the loop section 9, and the proper openings 4' thereof being positioned over the lugs 11, for securing the lower ends of the collar sections in their 85 proper adjusted positions.

It will be seen that the hames, not shown, but which are positioned over, and carried by the collar, may be removed simultaneously with the collar, thereby obviating the 90 necessity for removing the collar and hames separately.

From the foregoing it is obvious that a collar constructed in accordance with the present invention may be used on various 95 sized horses, with a perfect fit, due to the fact that the sections thereof may be expanded or contracted to the proper fit, around a horse's neck.

Having thus described my invention, 100 what I claim is:—

In an adjustable collar, opposed padded sections, the lower end of one of said sections being formed into an apertured tongue, a buckle secured to the opposite collar section, said buckle including a body portion, a loop extending upwardly and at right angles to the body portion, lugs formed on the body portion, said lugs extending upwardly therefrom and spaced from the loop, 110 said lugs being in parallel relation with the loop, the tongue adapted to extend through

the loop and engage over the lugs, for holding the tongue within the loop, and the upper ends of the lugs terminating at points above the plane of the lower edge of the loop to normally prevent displacement of the tongue.

In testimony that I claim the foregoing

as my own, I have hereto affixed my signature in the presence of two witnesses.

JOHN L. REAM.
